UNITED STATES PATENT OFFICE.

MICHELE OROFINO, OF PHILADELPHIA, PENNSYLVANIA.

BATH-TUB APPLIANCE.

1,197,657.

Specification of Letters Patent. Patented Sept. 12, 1916.

Application filed January 11, 1916. Serial No. 71,400.

To all whom it may concern:

Be it known that I, MICHELE OROFINO, a citizen of the United States, residing at Philadelphia, in the county of Philadelphia and State of Pennsylvania, have invented a certain new and useful Bath-Tub Appliance, of which the following is a specification.

The present invention relates to bath tub appliances and has reference more particularly to a chair for use in conjunction with a bath-tub as an aid to bathing, and the objects of my invention are: first, to provide a comfortable seat or support whereby a person using a tub for bathing purposes may remove a part of the body from the water as desired while remaining in a sitting position, thus avoiding the necessity of standing up in a slippery tub; second, to provide means to facilitate bathing the lower extremities of a person while taking a bath; third, to provide a collapsible or foldable support to be used in conjunction with a bath-tub and which can be compactly folded so that it may be conveniently stored.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Similar numerals of reference indicate corresponding parts.

Figure 1 represents a perspective of a bath-tub chair embodying my invention, the same being shown in operative position within a tub. Fig. 2 represents a plan of the chair frame, the seat being indicated in dotted lines. Fig. 3 represents a side elevation of the chair. Fig. 4 represents a front elevation of the same. Fig. 5 represents the chair in folded condition, and Fig. 6 represents a modification.

The device of my invention comprehends broadly a seat or supporting surface, and a frame, preferably capable of being col-

lapsed, for maintaining the seat in operative position within a bath-tub when required.

1 designates the seat body of the chair which may be of any suitable or desired shape to suit requirements, though in the present instance, it is provided with an opening 2 extending through the seat as will be apparent. As here shown the opening 2 is in the nature of a relatively large recess formed in the front edge of the seat so that only certain parts of the body rest directly upon the seat and the remaining parts are exposed and readily accessible for washing. A seat formed with an opening of this character is furthermore advantageous and desirable in hospital work for irrigating work, douches or the like. The seat body 1, as here shown, is fixedly secured to a suitable frame of metal having side parts 3 projecting to the rear of the seat and terminating respectively in hooks 4, the general contour of which is designed to conform to the configuration of the edge of the tub with which the device is used. In order to avoid marring or scratching the surface of the tub, I preferably provide shields 5 of rubber or material serving the same purpose which may be slipped over the hooks as will be understood.

6 designates the legs of the chair, of which I prefer to employ two, both being pivoted to the frame 2 at the front and having suitable feet 7 of rubber or material of a suitable nature to avoid scratching of the painted or enameled surface and to prevent slipping of the chair. The legs 6 are preferably braced against side thrust by the bridge members 8 or the like, while the side bars 9

and 10 control the bracing of the legs when the latter are swung to supporting or operative position. It will be noted that each pair of side bars is pivoted together at 11 while the opposite ends are respectively pivoted to the frame 2 and the legs 6. By this construction, it will be evident that one side bar of each side may be reversed and turned to lie adjacent its component member, thus bringing the legs 6 to a folded position substantially parallel to the bottom of the seat and in close proximity thereto. Thus the de-

vice may be folded into a very compact condition when not in use and conveniently put away until required. If desired, it may be

hung from a suitable support ready for use at any time and in Fig. 5, I have so shown the device and indicated wherein the rod 12 may serve as a rack for towels or other articles. Ordinarily the rod 12 serves to reinforce and strengthen the supporting action of the hooks 4, since in operative position it rests against the inner wall of the tub thereby distributing the strain and relieving the frame materially.

10 In connection with the side parts 3, it will be noted that these are preferably reversely bent and extended rearwardly as shown at 13 at substantially the center line of the seat being connected together by rivets 14 or like fashioning means and finally join the rear bar 15 of the frame, thus providing a strong and substantial support for the seat proper. It will further be seen that the rearward extensions 13 are of suitable contour to conform to the recess or opening 2 and consequently the frame does not interfere or obstruct the said opening 2.

When the device is not in use, it is usually 25 folded into compact form and stored in a convenient place and when needed it can be quickly and readily made operative by lowering the legs 6 to proper supporting position and setting the pivoted brace bars 9 and 10. In this condition, it is placed in the tub with the hook extension arms 4 seating upon the edge of the tub, thereby insuring a stable and effective support for any one using the tub.

30 It will now be apparent that I have devised a complete unitary device of simple construction and adapted to be effectively employed in connection with a bath-tub

whereby bathing or the like may the more easily and readily be carried out.

40 What I claim is:

1. A chair for bath-tubs comprising a seat body having a bounding edge of substantially curved contour provided with a relatively deep recess or opening at the front 45 part, a pair of legs pivoted to said seat for supporting the front part of said seat body in normal position and adapted to be folded into close proximity to said seat in inoperative position, rigid brace members connecting said legs, collapsible brace bars between the seat body and each leg and extension members projecting at the rear of said seat body and provided with means to engage the edge of a bath-tub to rigidly support 50 said seat body at the rear.

2. A chair for bath-tubs comprising a seat body having a relatively deep recess or opening at the front part, a metal frame forming a support for said seat body, said frame being shaped to leave said opening unobstructed, a pair of legs pivoted to said frame, one at either side of said opening, rigid brace members connecting said legs, collapsible brace bars between said leg and said frame and extension members formed as an integral part of said seat body and provided with means for engaging the edge of a bath-tub for supporting the rear part of said seat body.

70 In testimony whereof, I have hereunto signed my name.

MICHELE OROFINO.
